UNITED STATES PATENT OFFICE

JOHN LE VALLEY, OF PAINTED POST, NEW YORK, ASSIGNOR TO INGERSOLL-RAND COMPANY, OF JERSEY CITY, NEW JERSEY, A CORPORATION OF NEW JERSEY

COOLING-WATER REGULATOR

Application filed December 1, 1927. Serial No. 236,989.

This invention relates to regulators, and more particularly to regulators for controlling the supply of cooling water to the water jackets of air compressors and the like.

While this invention has many applications, it is particularly desirable for use on compressors and such apparatus which are continuously operated preferably at a constant speed, but which are arranged to be unloaded periodically. During such unloaded periods, there is relatively little heat developed in the compressor cylinders and therefore no cooling water is necessary for the water jackets.

It is an object of this invention to enable the supply of cooling water to be discontinued automatically during the unloaded period of the compressor and to automatically turn on the supply of such water when the compressor is again loaded.

Other objects and advantages of the invention will be in part obvious and in part pointed out hereinafter.

In the drawings accompanying the specification and in which similar reference characters refer to similar parts,

Fig. 1 is a side elevation of a compressor provided with a cooling water regulating apparatus constructed in accordance with the practice of the invention, the water valve and controlling pilot valve being shown in longitudinal section, and

Figure 2 is a sectional elevation of the auxiliary valve which controls the pilot valve.

Referring to the drawing, the cooling water regulating apparatus is shown associated with an air compressor A which is preferably of the type which is continually operated from the constant speed motor (not shown) and which may be provided with unloading apparatus (not shown) of any suitable type as is well known to discontinue the out-put from said compressor A when the pressure reaches a predetermined maximum. The compressor A is adapted to deliver com-

pressed air or other motive fluid through a discharge pipe B to a receiver C. The compressor A is adapted to be cooled by water entering at a suitable supply pipe D.

The compressor A need only be cooled while it is compressing air since when unloaded there is comparatively no heat developed. As is usual, the compressor A is unloaded so that no air is compressed when the pressure in the receiver C reaches a predetermined maximum and accordingly by this invention, the water is shut off by a water valve E when the pressure in the tank C reaches a predetermined maximum. The valve E is interposed between the pipe D and the water supply pipe line F.

The water valve E includes an outer casing G having a water passage H communicating with the pipes D and F. A wall J is provided in the passage H having an aperture K forming a seat for a longitudinally movable poppet type valve L normally pressed to its seat by a coil spring O interposed between the valve L and a pipe plug P screwed into a central aperture Q in the casing G. The valve L is provided with a stem R extending through a boss S in the upper wall T of the water passage H and is guided thereby. At its end the stem R is provided with a balanced portion U which is adapted to contact with a diaphragm V sealed on the upper face of the casing G by means of a cover W held in place by suitable bolts X.

The cover W forms a chamber above the diaphragm V and is provided with a pipe connection Y to a pilot valve Z.

The pilot valve Z is adapted to control the flow of motive fluid from the out-put of the compressor A which is delivered to the receiver C and thence to the chamber formed by the diaphragm V and the cover W. To this end, a pipe b is connected to the receiver C and to the pilot valve cover c. The pilot valve Z comprises a body portion d having a longitudinal bore e terminating in a larger

central bore *f* at the junction of which is formed a seat *g* for a ball check valve *h*. The cover *c* is screwed to the body member *d* as at *j* and holds in place on the body member *d* a perforated diaphragm or strainer *k* through which the air or motive fluid passes from the pipe *b* to the longitudinal central bore *e*. The larger bore *f* of the body member *d* is threaded to receive a plug *o* having 5 at its inner end a seat *p* for the ball valve *h*. The plug *o* acts as a guide for a stem *q* adapted to press against the ball valve *h* at one end and carries at its other end a flange *r* contacting with the diaphragm *s* held in 10 place by means of a cap *t*.

The ball valve is adapted to be seated by means of the stem *q* on the seat *g* by pressure of motive fluid exerted against the diaphragm *s*. Normally the ball valve is held to its seat 15 *p* of the plug *o* by means of a coil spring *u* in the bore *e*. The stem *q* has a longitudinal groove *v* providing a passageway from the bore *f* to an end chamber *w* in the body portion *d* and of which the diaphragm *s* forms 20 one side. The chamber *w* communicates with atmosphere through a suitable port *x*. Thus when the valve *h* is off its seat *p* any motive fluid under pressure within the chamber between the diaphragm *V* and the cover 25 *W* may be exhausted to atmosphere by way of the groove *v*. The cover *t* is provided with an aperture *y* through which motive fluid under pressure may be admitted from a pipe *z* to actuate the diaphragm *s*.

30 The admission of motive fluid to the pipe *z* is accomplished by means of an auxiliary valve 2 which may be of any well known type, such as that shown in Patent No. 1,138,278 granted May 4, 1915 to J. H. Castle and W. G. 35 Rogers. The motive fluid from the receiver *C* is transmitted to the auxiliary valve 2 by a pipe *3*.

Referring now more particularly to Figure 40 2 in which is shown an auxiliary valve designated generally by 2 and which, constructed in accordance with the practice of the aforesaid patent, comprises a casing 4 having a bore 5 therethrough. In one end of the bore 5 is threaded a plug 6 which serves as a guide 45 for a spring 7 disposed therein to act against a movable spring seat 8.

In the opposite end of the bore is threaded a hollow plug 9 to the outer end of which is connected the pipe 3.

50 Within the bore 5 is a valve seat 10 for a valve 11 adapted to control the flow of pressure fluid from the receiver to the pilot valve *Z* and its exhaust from the pilot valve to the atmosphere in a well understood manner.

55 In the operation of the compressor, as soon as pressure starts building up in the receiver *C* motive fluid passes through the pipe *b* and through the strainer *k* into the pilot valve *Z*, the ball check valve *h* being held off its seat *g* by means of the spring *u*. Motive fluid

therefore passes into the bore *f* and thence through the pipe *Y* to the diaphragm *V* depressing the valve *L* and permitting cooling water to flow from the pipe *F* to the pipe *D* and into the compressor *A*. When the pressure in the receiver *C* reaches a predetermined maximum, and at which time the compressor may be automatically unloaded, the auxiliary valve 2 being supplied with motive fluid through the pipe 3 operates and supplies motive fluid to the pipe *z* and thence to the diaphragm *s*. The flange *r* is pressed against by the diaphragm *s* causing the stem *q* to push the ball check valve *h* to its seat *g* cutting off the supply of motive fluid from the pipe *b* to the diaphragm *V* and allowing the accumulated air in the cover *W* to escape by way of the groove *v* in the stem *q* to the chamber *w* and thence to atmosphere through the vent port *x*. Since the pressure on the diaphragm *V* is removed the spring *O* presses the valve *L* to its seat *K* cutting off the supply of water flowing through the chamber *H* and discontinuing the cooling of the compressor *A*. It is understood of course, that this system is 70 preferably associated with any suitable well known type of unloading apparatus (not shown) for the compressor *A* which discontinues the out-put of motive fluid from the compressor *A* when the pressure in the receiver *C* reaches the predetermined maximum at which the auxiliary valve 2 is set to operate. Upon lowering of the pressure in the receiver *C* the auxiliary valve, as is well known, returns to its normal position cutting off the supply of motive fluid to the pipe *z* and exhausting the pressure fluid to atmosphere. The spring *u* returns the ball valve *h* to its seat *p* closing communication between the bore *f* to atmosphere and again allowing motive fluid to pass the seat *g* to operate the diaphragm *V* depressing the valve *L* and again establishing flow of cooling water from the supply pipe *F* to the pipe *D*.

Thus by the above construction are accomplished among others, the objects hereinbefore referred to.

I claim:

1. In a cooling water regulating apparatus for compressors and the like, the combination of a water valve, valve means normally open for causing pressure fluid to open said water valve at all pressures below a predetermined maximum, and means operable at pressures above a predetermined maximum to render said last mentioned means inoperative.

2. In a cooling water regulating apparatus for compressors and the like, the combination of a water valve, a pilot valve to open at all pressures below a predetermined maximum to supply motive fluid for holding said water valve in its open position, and means operable at pressures above a predetermined maximum for closing said pilot valve.

3. In a cooling water regulating apparatus for compressors and the like, the combination of a water valve, a pilot valve to open at all pressures below a predetermined maximum to supply motive fluid to said valve for holding the same open, and an auxiliary valve operable at pressures above a predetermined maximum for closing said pilot valve.

4. In a cooling water regulating apparatus for compressors and the like, the combination of a water valve, a diaphragm for controlling the opening of said valve, a pilot valve to open and to remain open at all pressures below a predetermined maximum for admitting motive fluid to said diaphragm to open the water valve, and an auxiliary valve for closing said pilot valve.

5. In a cooling water regulating apparatus for compressors and the like, the combination of a water valve, a diaphragm connected to the valve for controlling the opening of the same, a pilot valve normally admitting motive fluid to the diaphragm to open the water valve, and an auxiliary valve operable at pressures above a predetermined maximum for closing said pilot valve by supplying motive fluid to the same.

6. In a cooling water regulating apparatus for compressors and the like, the combination of a water valve, a spring biased to its closed position, a diaphragm connected to said valve and adapted when compressed to open the same, a pilot valve to normally occupy an open position for supplying motive fluid to said diaphragm to open the water valve, said pilot valve being connected to a diaphragm, and an auxiliary valve operable at pressures above a predetermined maximum to supply fluid to said last mentioned diaphragm to close said pilot valve.

7. In a cooling water regulating apparatus for compressors and the like, the combination of a water valve, a pilot valve to be normally open to supply motive fluid to the interior of the water valve to open the same, and means operable at pressures above a predetermined maximum for simultaneously closing said pilot valve and opening the interior of the water valve to the atmosphere to discharge pressure fluid therein for closing the same.

8. In a cooling water regulating apparatus for compressors and the like, the combination of a water valve to normally open for supplying motive fluid to the interior of the water valve to open the same, and means for simultaneously closing the pilot valve and communicating the interior of said water valve with the atmosphere.

9. In a cooling water regulating apparatus for compressors and the like, the combination of a casing having a passage for cooling water and a seat in the passage, a valve cooperating with the seat to control the passage, a spring tending to close the

valve, a diaphragm connected to said valve, said diaphragm forming with the casing a chamber, a pilot valve to be normally held open for supplying motive fluid to the chamber to depress said diaphragm and open said water valve, an air vent in said pilot valve, and means for simultaneously closing said pilot valve and communicating the interior of said chamber with said air vent.

In testimony whereof I have signed this specification.

JOHN LE VALLEY.
